UNITED STATES PATENT OFFICE.

CORAL NOVELLO WESTWOOD, OF NANAIMO, CANADA.

TYPE-WRITING MACHINE.

SPECIFICATION forming part of Letters Patent No. 628,451, dated April 18, 1899.

Application filed November 5, 1897. Serial No. 657,579. (No model.)

To all whom it may concern:

Be it known that I, CORAL NOVELLO WESTWOOD, of Nanaimo, British Columbia, Canada, have invented a new and useful Improvement 5 in Type-Writer Attachments, of which the following is a specification.

It is the object of this invention to provide improved means for column-spacing, line-spacing, and back spacing in type-writing, 10 say, on machines of the Remington and Caligraph type. The invention is embodied in mechanism attached to the right-hand side of such a machine and which is so connected with the rotary cylindrical platen and its reciprocal carriage as to adjust one or both, as required, for effecting either column, line, 15 or back spacing. The construction, arrangement, and operation of such mechanism are hereinafter described, and shown in the accompanying drawings, (three sheets,) in which—

Figure 1 is an end view showing my improved attachment applied to a Caligraph type-writing machine. Fig. 2 is a side or face view of the same. Fig. 3 is an enlarged horizontal section, on line 3 3 of Fig. 2, of a portion of the attachment. Fig. 4 is a vertical section on line 4 4 of Fig. 3. Fig. 5, Sheet 2, is a rear elevation of the attachment applied to a Caligraph machine. Fig. 6 is an enlarged 20 face view of a portion of the apparatus, part being broken away. Fig. 7 is a detail section of parts shown in Fig. 6. Fig. 8, Sheet 3, is a plan view of the attachment. Figs. 9 and 25 10 are plan and side views illustrating the treadle mechanism. Fig. 11 is an enlarged longitudinal section of the platen and some of its attachments.

I will first describe the means for releasing the platen and allowing it to run forward and 30 stop it at certain points.

A cylinder 1 (see Figs. 1, 2, and 8) is secured by screws to the front and right-hand side of the type-writer frame 2. In the vertical face of said cylinder 1 a series of push-keys 3 are 35 arranged in a circle to work in horizontal guides, their enlarged heads bearing numerals "5," "10," "15," and other multiples of five corresponding to numbers inscribed on the scale or gage plate 2^a, Fig. 2, ordinarily 40 used on type-writing machines. The heads of these keys 3 are adapted to bear upon the outer ends of a series of levers 4, Fig. 3, ar-

ranged radially on the face of the cylinder 1, with their convergent inner ends engaging jam-nuts 5, applied to a shaft 6. The levers 55 are pivoted on a wire extending around a circular flange. The shaft 6 passes transversely through the cylinder 1 and across the end of the type-writer frame 2 and is further supported horizontally by a bearing on the latter, as shown best in Fig. 1. On the rear end of the shaft 6 are mounted a drum 13 and ratchet-disks 8 9, which will be hereinafter described in detail. The shaft 6 is slidable longitudinally and also rotatable. It is slid 60 forward by depression of a key or push-pin 3, which thereby tilts a lever 4, which in turn acts on the jam-nuts, as shown by dotted lines, Fig. 3. The object of this movement of the shaft 6 is to momentarily release the 70 ratchet-disks 8 9 from engagement with a pawl 10, Fig. 5. The pawl proper is pivotally attached to a vertical arm or standard 10^a, that forms a fixed attachment of the rocking bar or frame 11 usually employed on type-writers of the class hereinbefore referred to. Consequently the pawl 10 oscillates laterally with said bar 11 as the latter rocks, and it is provided with a plate-spring 12 for holding it 75 normally engaged with the ratchet-disks 8 80 and 9.

The drum 13, Fig. 1, is secured on shaft 6 and has lateral flanges, as shown. The ratchet-disk 9, Fig. 6, is secured adjustably to the outer side of the drum 13 by means of screws 14, that 85 pass through arc slots 15. The object of this adjustment of the disk 9 is to enable it to be set circumferentially, whereby to coincide with the ratchet-disk 8 and form part of the mechanism for moving the carriage forward step by 90 step, which mechanism I shall now describe. It will be understood that said disk is normally fast or fixed on the drum 13 when in use. The other disk 8 is, however, loosely mounted on the shaft 6, but its circumferential movement is limited by screws passing through arc slots 17 and entering shouldered studs or bosses 18, Fig. 7, forming part of the fixed disk. The disks 8 and 9 are separated by a space sufficient to receive a small spiral 100 spring 19, Fig. 6, whose ends are connected with them, respectively, by means of screws or other suitable fastenings. It is apparent that the spring 19 normally holds the outer disk 8

in the position shown in Fig. 6, in which its teeth register or coincide with those of the inner disk 9, so that the pawl 10 may slide laterally from one disk to the other when oscillated by the rocking bar 11, as before stated. In further explanation of this part of the attachment I will state that when the pawl 10 is canted or moved inwardly it is carried from the loose ratchet 8 into engagement with the fixed ratchet 9, and the former, 8, being thus left free is rotated and carried forward one notch or tooth by the tension of spiral spring 19. On return of pawl 10 to its normal position in contact with the loose ratchet 8 the platen-frame is allowed to move forward one space by means of the arc slots 17 in ratchet 8. Thus the movement of the pawl 10, as described, allows for a letter or letter-space in the writing done by the machine. When the shaft 6 is drawn forward by a push-key 3 and lever 4, as before described, the loose disk 8 may be freed from the pawl 10. A cord or suitable wire cable 20, Fig. 5, is secured at one end to the drum 13 and at the other to the platen-frame 21, passing intermediately over an idle pulley 22 and through a guide 23, whereby it will be seen that the shaft 6 is rotated when the platen-frame 21 is slid. A binding-screw serves to secure the cable to platen-frame and as a means for taking up slack when required. This cable 20 is provided with a spring attachment 24, preferably formed of a spiral spring arranged between two disks that slide on rods to which the respective divided portions of the cable 20 are attached. The function of the spring 24 is to relieve shock on the cable 20 when operating the platen 25—that is to say, when the movement of the platen is checked. It will be understood that the function of the pull cord or cable 20 is to produce forward and backward movement—i. e., reciprocation of the platen.

Returning now to Fig. 3, it will be seen that the shaft 6 has a radial arm 26, which is fixed thereon, and hence moves with it. When a key 3 is pushed in, it projects into the rotary path of this arm, and therefore serves as a stop for limiting the rotation of said shaft. A pull-cord 27 is applied to the drum 13 and winds thereon in a direction opposite the cable 20. This pull-cord is connected with a treadle, as hereinafter described.

The following-stated conjoint operation of the parts before described will now be comprehensible. Say it is desired to allow the platen to run forward (or to the left) until the pointer, Fig. 2, is opposite the numeral "50" on the scale-bar 2^a, it being assumed the platen has been drawn back to the right-hand position shown in said figure. The operator presses inward that one of keys 3 whose head bears said numeral, and thus tilts the connected lever 4, which in turn acts against the jam-nuts 5 and draws the shaft 6 forward, together with its attachments—namely, the arm 26, drum 13, and ratchet-disks 8 and 9,

which latter are thus freed from the pawl 10. Then the shaft 6 is free to rotate, so that the platen 25 and its carriage 21 move forward or to the left until the arm 26 of shaft 6 in the course of its rotation strikes the key 50, (which is still held depressed by the operator,) and thus the platen-carriage is stopped with the pointer at "50" on the scale. If now the key 3 be released, the shaft 6 will slide back to its normal position, being retracted by the spring 28, which acts against a collar on said shaft, and the pawl 10 will then reengage the outer ratchet 8, as before. The operator may return the platen 25 to the former starting position by pressing the treadle so as to pull the cord 27, whereby the drum 13 is rotated and the cable 20 wound on the same, which applies to the platen-carriage the force necessary to move it to the right.

I will now describe the means for moving the platen 25 backward to a point in any space intermediate the numeral "5" and its multiples. As shown best in Figs. 3 and 4, a lever-arm 30 is mounted loose on the shaft 6 and projects through a lateral slot in the cylinder. It is held normally at the top of said slot by a wire spring 31, suitably connected with it and the cylinder. A ratchet-disk 32 is fastened by a set-screw on the shaft 6, and a pawl 33 is pivoted to said lever and adapted to engage it, as shown in Fig. 4. A stud or pin 34 holds the pawl out of engagement when the lever 30 is raised; but when the latter is depressed the spring 35, which bears on the heel of the pawl 33, throws its point inward, and thus the ratchet 32 and shaft 6 are rotated. It is apparent this will also rotate the drum 13 and wind on the cable 20, whereby the platen-carriage will be drawn to the right. Thus back spacing may be effected—that is to say, suppose the platen to have been adjusted to the numeral "50," as before, and it be desired to move it back to "48" the lever 30 is twice depressed in order to rotate the ratchet-disk 32 the distance equivalent to two spaces or notches on the latter. In other words, the downward throw of the lever 30 turns the shaft 6 and drum 13 backward, and thereby pulls on the cable 20, which in turns draws the platen-carriage back one space.

I will now describe the means for effecting line-spacing, which is effected, as usual, by rotating the platen 25 the required distance. The platen is mounted slidably, but not rotatably, on a shaft 36, Fig. 8, having a ratchet-disk 37 fixed on its right-hand end, to which disk a rotative step-by-step motion is imparted by a lever 38 and spring-pawl 39 through the medium of a pull-cord 40, connected with a treadle, as will be hereinafter described. The shaft 36 does not slide, but is free to rotate, having its bearings in one end of the platen-carriage and in the vertical plate or flange 41, forming a part or attachment of a bracket 42, which is attached to the right-hand end of the frame 2 and supported by an oblique brace 43. The shaft 36 is

grooved throughout its length, and a feather 44, Fig. 11, attached to the extended hub 45 of the platen enters and slides in such groove. A sleeve 46 is interposed between the shaft 36 and hub 45 to take the friction and wear.

It will be apparent that if the operator moves the treadle so as to pull the cord 40 the lever 38 will be depressed and its pawl 39 caused to engage the ratchet 37, thereby turning the shaft 36 and platen 25 together, so that the latter is adjusted as required for line-spacing. The lever 38 is thrown up to its normal position by a spring 46^a, Fig. 1. The said lever works in a keeper attached to bracket-flange 41.

I propose to employ any suitable treadle mechanism to operate the pull-cords 27 and 40. In Figs. 9 and 10 I show two treadles that may be advantageously employed. The pull-cords pass down through the table 47 and over idle pulleys 48 to lateral arms 49 of the respective treadles proper. Each of these latter is formed of a vertical shaft 50, set at its end on pivots attached, respectively, to the table and floor and provided with lateral foot- rests 51. Spiral springs are attached to the head of each post or shaft 50 for throwing it back to normal position. By applying a foot to each rest 51 the operator may rotate the shafts, and thus cause their arms 49 to pull the cords 27 40 when required to return the platen-carriage or to rotate the platen for spacing between the lines. The dotted lines, Fig. 9, illustrate the movements of the treadle mechanism so far as requisite to enable the operation to be understood. When the platen has been returned by operating a treadle to pull-cord 27, its arm or check 52, Figs. 2 and 8, strikes a rubber buffer 53, attached to the machine-frame 2 by means of a supporting-bracket 54.

Recapitulating, spacing between the lines is effected by a treadle mechanism operating through the pull-cord 40 on the lever 38 and ratchet 37, whereby the shaft 36 and platen 25 are rotated. The operation of the other treadle draws the platen back to starting position, and the hand or thumb lever 30, ratchet 37, and shaft 36 serve to bring the platen back 50 one or two spaces.

What I claim is—

1. In a type-writing machine, the combination with a platen carriage or frame adapted to slide endwise, of mechanism for releasing said frame and allowing it to move to a selected point and there stopping it, which consists of a transverse shaft, a ratchet-disk mounted on the latter, a pawl engaging the disk, means for shifting the shaft and disk to release the latter from engagement with the pawl, means for connecting the platen-frame and aforesaid shaft so that the latter rotates as the former slides, and a stop mechanism applied to the shaft, for arresting its rotation as the frame reaches the predetermined point, substantially as shown and described.

2. In a type-writing machine, the combina-

tion with a platen carriage or frame adapted to slide endwise, of mechanism for releasing said frame and allowing it to move to a selected point and there stopping it, which consists of a transverse shaft, a ratchet-disk mounted on the latter, a pawl engaging the disk, a lever engaging the shaft for drawing it forward, a push-pin bearing a numeral corresponding to one on the ordinary scale of the machine, a stop-arm on said shaft which such push-pin is adapted to engage, when the shaft is drawn forward, a pulley on the shaft, and a cable connecting the pulley and platen-frame, substantially as shown and described.

3. In a type-writing machine, the combination with a platen carriage or frame adapted to slide endwise, of mechanism for releasing said frame and allowing it to move to a selected point and there stopping it, which consists of a transverse shaft, a ratchet-disk mounted on the latter, a pawl engaging the disk, a series of pivoted levers arranged radially around said shaft, at the front of the machine, and loosely engaging the same at their inner ends, a radial, rotary arm on said shaft, a series of push-pins working in a horizontal guide, each being arranged beside one of said levers and adapted to engage, when pushed in, with the rotary arm aforesaid, a pulley on the shaft, and a cord extending therefrom to the platen-frame, substantially as shown and described.

4. In a type-writing machine, the combination with a slidable platen, of a transverse slidable shaft, and means for drawing the same forward and stopping it at a predetermined point when rotated, of a pulley mounted on the latter, a cable connecting the pulley and platen, two ratchet-disks arranged side by side on the shaft, and a pawl from which the disks are disengaged when the shaft is drawn forward, said pawl being rigidly attached to a rock-bar forming part of the type-writer mechanism, and one of said disks being adapted to yield and rotate backward a part of a revolution, and a spring for holding it in normal position, substantially as shown and described.

5. In a type-writing machine, the combination with a slidable platen, a transverse slidable shaft and means for rotating and stopping the latter, of two ratchet-disks, one of which is fixed and the other loose on said shaft, a spring and stop for retracting and limiting the rotation of such loose disk, a pulley and cable connecting it with the platen, and a pawl adapted to engage and disengage from said disks as shown and described.

6. In a type-writing machine, the combination with a slidable platen, a transverse slidable shaft and means for rotating and stopping the latter, of two ratchet-disks, one of which is fixed and the other loose on said shaft, a spring and stop for retracting and limiting the rotation of such loose disk, a cable connecting said pulley with the platen and a spring interposed between sections of said cable, as and for the purpose specified.

7. In a type-writing machine, the combination with a slidable platen of a transverse slideable shaft, means for drawing the latter forward, a pulley on the shaft and a cable connecting said pulley with the platen, of a ratchet-disk mounted on the shaft, a thumb-lever arranged radially to the latter, and a pawl pivoted to the lever and adapted to engage the disk, for rotating the shaft for the purpose of back spacing substantially as shown and described.

8. In a type-writing machine, the combination with a slidable platen of a transverse slideable shaft, means for drawing the latter forward, a pulley on the shaft and a cable connecting said pulley with the platen, of a ratchet-disk mounted on the shaft, a thumb-lever arranged radially to the latter, and a pawl pivoted to the lever and adapted to engage the disk, a spring for throwing the pawl into engagement with the disk, a fixed pin

for holding it out of such engagement when the lever is being retracted, and a spring for retracting said lever after the manual depression required to effect back spacing, as 25 shown and described.

9. In a type-writing machine, the combination with a slidable platen-carriage, a shaft, and a connection between said platen-carriage and shaft whereby the latter will rotate when the former is slid, of a ratchet-disk mounted on said shaft, a thumb-lever arranged radially on the latter, and a pawl pivoted to said lever and arranged to engage the disk whereby to rotate the shaft backward for 30 the purpose of back spacing, as shown and described.
